FOLDING DRYING RACK

Clarence W. Swanson, Denver, Colo.

Application February 19, 1946, Serial No. 648,738

8 Claims. (Cl. 312—185)

1

This invention relates to a folding laundry device for household installation, and has for its principal object the provision of a neat, compact, and highly efficient unit which will fold completely into the thickness of the usual household partition, and which can be extended to provide a supporting bar for large pieces such as table-cloths, sheets, etc., and a drying rack for drying pieces before ironing.

Another object of the invention is to provide a drying rack which, when folded, will occupy but a minimum of space in the room partition; which, when extended, will provide four sets of adjustable drying arms for supporting the pieces to be dried; and which can be quickly and easily erected and folded.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the complete invention in the partially extended position;

Fig. 2 is a face view of the folding household laundry device with the various elements in their folded position;

Figs. 3 and 4 are vertical sections, taken on the lines 3—3 and 4—4, respectively, in Fig. 2;

Fig. 5 is a detail section looking upwardly on the line 5—5, Fig. 2;

Fig. 6 is a similar detail section looking downwardly on the line 6—6, Fig. 7; and

Fig. 7 is a detail section, taken on the line 7—7, Fig. 6.

The device is contained within a wall box 10 which may be secured on or set into a wall. As illustrated, the box 10 is set into a wall 11 and provided with a suitable frame 12 which surrounds the box on the surface of the wall.

The device is closed when it is not in use by means of suitable hinged doors 13. A vertical partition 14 divides the box into two compartments, which will be herein designated an ironing board compartment 15 and a rack compartment 16.

While the device as illustrated combines the ironing compartment and the rack compartment, it is, of course, possible that these two compartments could be separated and used independently of each other; that is, in some installations only

2

the rack compartment would be installed, and in others only the ironing board compartment.

The ironing board compartment is designed to contain a main ironing board 17 and a secondary ironing board 18. The secondary board is provided for ironing small articles and for entering sleeves of garments, etc. The main ironing board is hinged as shown at 21 to a cross block 19 secured to a vertically movable backing frame 20. The secondary ironing board is hinged to the upper edge of the backing frame 20. The backing frame is vertically movable in the box 10 behind vertical guide strips 22.

This enables the ironing boards to be raised after they have been opened from the box 10 to enable a diagonal supporting leg 23 to be inserted into the bottom of the box 10 to support the ironing board. The leg 23 is mounted on a U-shaped hinge member 24 beneath the bottom of the board 17, which enables its position to be changed with relation to the board to properly position it when used as a brace. The secondary board 18 is supported when in use from the main board 17 by means of a hinged leg 25 which swings downwardly and rests on the main board. Both boards are supported in their folded position by means of turn buttons 26.

The rack compartment 16 serves to conceal a sheet-supporting bar 27 which is hinged at one extremity on a hinge rod 28 extending across the compartment 16. The hinged extremity is provided with a bracket 29, also mounted on the hinge rod 28 to maintain the bar 27 at right angles thereto. The bar 27 is supported in the horizontal position by means of a folding toggle brace 30 secured to the side of the box 10. The bar 27 is positioned to one side of the ironing board 17 and above the latter to conveniently support large pieces such as sheets, bed spreads, tablecloths, and the like, while being ironed.

The rack compartment 16 also contains a folding drying rack structure consisting of a channel member 31 which is hinged at its one extremity on a hinge pin 32 extending across the compartment 16. The channel member is supported in the horizontal position by means of a pair of toggle braces 33 which are pivotally secured at one extremity to the sides of the compartment 16, and at the other extremity to the sides of the channel member 31.

A box-like standard comprising two flat side members 34 connected at their ends is mounted on a horizontal pivot bolt 35 adjacent the outer extremity of the channel member 31 and between the two sides of the latter so that it may fold

therebetween. When turned to the vertical position of Fig. 1, the lower extremities of the sides 34 swing into a notch 36 formed in the bottom of the channel member 31 to stop the standard in the vertical position.

The standard supports four radial sets of clothes hangers, two upper sets 37 and two lower sets 38. The hangers of the lower sets 38 are mounted on hinge pins 39 in supporting brackets 40. The brackets 40 are in turn mounted on horizontal hinge pins 41. This construction allows the hangers 38 to be swung together into parallel relation, thence swung upwardly between the two side members 34. When the brackets 40 are swung downwardly, they fit into notches 36 in the sides of the channel member 31 to lock the standard in the vertical position.

The upper hangers 37 are similarly mounted in supporting brackets 42 adjacent the top of the side members 34. The supporting brackets 42 are each provided with a horizontally-extending hinge pin 43. The extremities of the hinge pins 43 are horizontally movable in horizontal grooves 44 extending across the inside face of each of the side members 34. A stop block 45 is positioned between and above the hinge pins 43.

When the hangers 37 are extended, the inner extremities of the bracket members 42 are positioned beneath the stop block 45, which prevents the hangers from swinging downwardly, as shown in Fig. 7. To fold the hangers, they are pulled outwardly, the hinge pins 43 traveling in the grooves 44 until the inner extremities of the bracket members 42 pass from beneath the stop block 45. The hangers then can be swung downwardly between the two side pieces 34.

In folding the device, the upper hangers 37 are first folded between the side members 34. The lower hangers 38 are then folded upwardly over the upper hangers and between the members 34. The latter members are then folded backwardly and downwardly into the channel member 31, and the latter is folded upwardly into the hanger compartment 16. A latch is provided for supporting the ironing board 17 at any desired elevation, as shown in Fig. 5. The latch consists of two bolt members 46 which are secured to the extremities of a latch operator 47 pivoted to block 19. Swinging the operator 47 forces the bolts 46 outwardly against the sides of the ironing board compartment 15 to support the frame 12 at any desired height therein.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A folding clothes hanger comprising: a supporting structure, an arm hinged to said structure so that it may unfold from a vertical to a horizontal position thereon; a standard hinged adjacent the free extremity of said arm to unfold from a horizontal to a vertical position thereon when said arm is in said horizontal position; a hanger bracket hinged to said standard to unfold from a vertical position parallel to said standard in such position to a horizontal position thereon; and a plurality of hanger bars hinged to said bracket to unfold from a parallel aligned position to radially flaring positions thereon.

2. A folding clothes hanger comprising: a supporting structure; an arm hinged to said struc-

ture so that it may unfold from a vertical to a horizontal position thereon; a standard hinged adjacent the free extremity of said arm to unfold from a horizontal to a vertical position thereon when said arm is in said horizontal position; a hanger bracket hinged to said standard to unfold from a vertical position parallel to said standard in such position to a horizontal position thereon; and a plurality of hanger bars hinged to said bracket to unfold from a parallel aligned position to radially flaring positions thereon, said arm having an open channel therein for receiving said standard when the latter is folded to the horizontal position thereon.

3. A folding clothes hanger comprising: a supporting structure; an arm hinged to said structure so that it may unfold from a vertical to a horizontal position thereon; a standard hinged adjacent the free extremity of said arm to unfold from a horizontal to a vertical position thereon when said arm is in said horizontal position; a hanger bracket hinged to said standard to unfold from a vertical position parallel to said standard in such position to a horizontal position thereon; and a plurality of hanger bars hinged to said bracket to unfold from a parallel aligned position to radially flaring positions thereon, said standard being hollow to receive said bracket and said hanger bars when folded to the vertical position thereon.

4. A folding clothes hanger comprising: a supporting structure; an arm hinged to said structure so that it may unfold from a vertical to a horizontal position thereon; a standard hinged adjacent the free extremity of said arm to unfold from a horizontal to a vertical position thereon when said arm is in said horizontal position; a hanger bracket hinged to said standard to unfold from a vertical position parallel to said standard in such position to a horizontal position thereon; and a plurality of hanger bars hinged to said bracket to unfold from a parallel aligned position to radially flaring positions thereon, said arm having an open channel therein for receiving said standard when the latter is folded to the horizontal position thereon, said standard being hollow to receive said bracket and said hanger bars when folded to the vertical position thereon.

5. A folding clothes hanger comprising: a supporting structure; an arm hinged to said structure so that it may unfold from a vertical to a horizontal position thereon; a standard hinged adjacent the free extremity of said arm to unfold from a horizontal to a vertical position thereon when said arm is in said horizontal position, said standard being hollow and having an open side; a lower hanger bracket hinged within the lower portion of said standard in said vertical position; an upper hanger bracket hinged within the upper portion of said bracket, said brackets being positioned to swing outwardly through the open side of said standard to a horizontal position; a plurality of hanger bars hinged in each bracket member to be extended radially therefrom; and means for supporting said brackets in a horizontal position.

6. A folding clothes hanger comprising: a supporting structure; an arm hinged to said structure so that it may unfold from a vertical to a horizontal position thereon; a standard hinged adjacent the free extremity of said arm to unfold from a horizontal to a vertical position thereon when said arm is in said horizontal position, said standard being hollow and having an open side; a lower hanger bracket hinged within the

lower portion of said standard in said vertical position; an upper hanger bracket; a movable hinge mounting said upper hanger bracket hinged within the upper portion of said standard, said brackets being positioned to swing outwardly through the open side of said standard to a horizontal position; a plurality of hanger bars hinged in each bracket member to be extended radially therefrom; and a downwardly projecting block in said standard above and to one side of the upper bracket, the movable hinge of the upper bracket allowing said upper bracket to be positioned beneath said block to support the upper bracket in a horizontal position.

7. A folding clothes hanger comprising: a supporting structure; an arm hinged to said structure so that it may unfold from a vertical to a horizontal position thereon; a standard hinged adjacent the free extremity of said arm to unfold from a horizontal to a vertical position thereon when said arm is in said horizontal position; a hanger bracket hinged to said standard to fold from a vertical position parallel to said standard in such position to a horizontal position thereon; and a plurality of hanger bars hinged to said bracket to unfold from a parallel aligned position to radially flaring positions thereon, said arm having an open channel therein for receiving said standard when the latter is folded to the horizontal position thereon, the sides of said channel being notched to receive said bracket to

maintain said standard in a vertical position and to maintain the bracket in a horizontal position.

8. A folding clothes hanger comprising: a supporting structure; an arm hinged to said structure so that it may unfold from a vertical to a horizontal position thereon; a standard hinged adjacent the free extremity of said arm to unfold from a horizontal to a vertical position thereon when said arm is in said horizontal position; a hanger bracket hinged to said standard to fold from a vertical position parallel to said standard in such position to a horizontal position thereon; a plurality of hanger bars hinged to said bracket to unfold from a parallel aligned position to radially flaring positions thereon; and independent releasable means for supporting said arm in its horizontal position, said standard in its vertical position, and said bracket in its horizontal position.
